US00D901455S

(12) **United States Design Patent** (10) **Patent No.:** **US D901,455 S**
Brunner et al. (45) **Date of Patent:** **** Nov. 10, 2020**

(54) **AUDIO LISTENING SYSTEM**(71) Applicant: **Apple Inc.**, Cupertino, CA (US)(72) Inventors: **Robert Brunner**, San Francisco, CA (US); **Rhys Bonahoom**, Burlingame, CA (US)(73) Assignee: **Apple Inc.**, Cupertino, CA (US)(***) Term: **15 Years**(21) Appl. No.: **29/690,031**(22) Filed: **May 3, 2019****Related U.S. Application Data**

(63) Continuation of application No. 29/615,900, filed on Aug. 31, 2017, now Pat. No. Des. 847,780, which is a continuation of application No. 29/565,174, filed on May 18, 2016, now Pat. No. Des. 796,487, which is a continuation of application No. 29/527,763, filed on May 21, 2015, now Pat. No. Des. 759,634, which is a continuation of application No. 29/493,738, filed on Jun. 12, 2014, now Pat. No. Des. 732,509, which is a continuation-in-part of application No. 29/441,335, filed on Jan. 3, 2013, now Pat. No. Des. 707,652.

Search Report for Taiwanese Application No. 099303307 dated Oct. 3, 2011.

Primary Examiner — Paula Allen Greene(74) *Attorney, Agent, or Firm* — Sterne, Kessler, Goldstein & Fox P.L.L.C.(57) **CLAIM**

The ornamental design for an audio listening system, as shown and described.

DESCRIPTION

FIG. 1 is a front perspective view of an audio listening system showing the claimed design;

FIG. 2 is a rear view thereof;

FIG. 3 is a front view thereof;

FIG. 4 is a left side perspective view thereof;

FIG. 5 is a left side view thereof; and,

FIG. 6 is a right side view thereof.

The broken lines in the figures show portions of the audio listening system that form no part of the claimed design.
